UNITED STATES PATENT OFFICE.

PHILIP RICHARDT, OF PRAGUE-KAROLINENTAL, AUSTRIA-HUNGARY, ASSIGNOR TO ZIVNOSTENSKA BANKA, OF PRAGUE, AUSTRIA-HUNGARY.

AUTOMATIC TELEPHONE CALLING DEVICE.

1,121,400.

Specification of Letters Patent. Patented Dec. 15, 1914.

Application filed November 25, 1912. Serial No. 733,461.

To all whom it may concern:

Be it known that I, PHILIP RICHARDT, subject of the King of Sweden, residing at Prague-Karolinental, Rokycangasse 32, 5 Bohemia, State of Austria-Hungary, have invented certain new and useful Improvements in Automatic Telephone Calling Devices, of which the following is a specification.

10 The number switch hitherto used and which is provided with a finger disk has been substituted already by many other devices, which facilitate the adjusting of the desired number. But the manipulation at 15 the said number switches yet remains complicated in comparison with hand operated systems and may sometimes give rise to misswitchings. The winding up of the said apparatuses by turning a crank must be regarded as being analogous with the movement of the inductor crank at the hand stations.

The object of the present invention is to render the manipulation at the automatic subscriber's stations likewise as simple as 25 in the case with the above named apparatuses, that is in such a manner that after the adjustment of the selecting device the seeking for the subscriber and the calling of the 30 same will be effected merely by taking off the receiver. Therefore the arrangement is such that on suspending the receiver a spring will be tensioned, which, on taking-off the receiver in case the selecting device 35 is adjusted causes the transmitting of current impulses. The apparatus, is furthermore arranged in such manner that the transmitting of current impulses does not take place when the receiver is taken off in 40 order to answer a call received at the particular telephone. The arrangement, is furthermore such that the action of suspending the receiver upon its hook automatically returns the selecting device to the 45 position of rest or what may be termed in idle position.

An example of the invention is illustrated in the annexed drawings.

Figure 1 shows the complete apparatus 50 in elevation. Fig. 2 is a plan view, Fig. 3 a side elevation with the levers for releasing the clock work and Fig. 4 a side elevation with the levers for releasing the selecting device. Fig. 5 shows the levers for releas-

ing the clock work in the different positions 55 and Fig. 6 the levers for releasing the selecting device in the different positions.

In the drawings it is assumed that a push-button selecting device is used and the impulse transmitting device consists of a 60 transmitter and an additional switch, such as the devices shown in my copending application bearing the Serial No. 708,507, the connections and wiring being likewise there- 65 shown, the movable contacts of which are secured upon the shafts 1 and 2 the shaft 1 being obliged to make one revolution and the shaft 2 to make three revolutions every time. As a matter of course a single impulse transmitter making only one revolution 70 may also be used, and also other convenient arrangements with suitable gearings etc may be made use of.

The receiver hook 3 (Figs. 1, 2) is capable of being turned about an axis 4 and is by 75 means of a pin or projection 5 coupled, so as to work only in one direction, with a toothed segment 6, upon which the driving spring 7 acts, so that the receiver hook 3 moving down carries with it the segment 6, 80 but being drawn by the spring 8 into a position indicated by dotted lines (Fig. 1) is allowed to perform this movement without any hindrance. The segment 6 engages a pinion 9 provided with a ratchet clutch 10 85 working in one direction. The pinion 9 is pressed by means of the spring 11 toward the second part of the clutch 10, with which the toothed wheel 12 is rigidly connected. The wheel 12 engages a pinion 13, which together with the wheel 14 and the locking disk 15 is rigidly secured upon the axle 1 which performs only one revolution. The 90 wheel 14 engages a pinion 16 which corresponds to the above mentioned ratio of gear- 95 ing and is mounted upon the shaft 2, from which a suitably constructed train of wheels 17, 18, 19 and 20 a fan wheel 21 is driven. The clock work is locked at the disk 15 by means of the lever 22, which engages the 100 said disk and is capable of revolving about the axle 32 (Fig. 5).

The push button selecting device may be imagined for example as being provided with push-buttons or the like which are arranged 105 in rows corresponding to position values and release each other in rows *i. e.* if a push button of one row is in depressed position

and another push button of the same row will be depressed the first named button will be released.

The clock work and selecting device are connected with each other mechanically in such manner that 1, during the adjusting of the selecting device the releasing of the clock-work is prepared; 2, on taking off the receiver the clock work will be released and 10 3, on suspending again the receiver the selecting device will be restored and the driving spring tensioned again.

In order to suit the first requirement stirrups 23 (Figs. 1, 3 and 5) are provided 15 at the selecting device, the said stirrups being in the lowermost position in case the buttons are in their position of rest, but engaging the edge of the cone or tooth 24, in case one button is being depressed, whereby a 20 bar 25 in connection with the stirrup 23 by means of a pin 47 will be lifted, so that the said bar lifts by its lug 26 the pin or projection 27 of a lever 28. By the lever 28 and the lever 29 which are fixed together upon 25 the same shaft 31, and by means of a bar 30 a two armed lever 33 is moved about the shaft 32. The lever 33 has on one arm a lug 34 and at the end of the other arm a pin 35, which is arranged in the same level with the 30 receiver hook 3 and is moved during the described movement of the lever system above the sloping curved surface of a lug 36 secured laterally on the receiver hook, as is shown by full lines in Fig. 5. If now the 35 receiver is taken off, after the remaining push buttons necessary for selecting a number have been depressed, the receiver hook 3 will be pulled by the spring 8 and carried into the position indicated by dotted lines, 40 whereby the pin 35 is forced to slide over the face of the lug 36. The lever 33 is thereby forced to move farther laterally so that it carries with it by its lug 34 the locking lever 22, which releases the disk 15 and 45 therefore releases the clock work (Fig. 5, dotted lines). The segment 6 will then be moved by the driving spring 7 and lifts finally the receiver hook by means of the pin 5 into the uppermost position indicated by 50 the upper dotted center line (Fig. 1). Meanwhile the lever 33 and therefore also the locking lever 22 are released again, and the said locking lever being pressed by means of the spring 37 toward the disk 15 55 will then lock the disk 15 again as soon as it has performed a complete revolution. If now the receiver be suspended again, it pulls the receiver hook down owing to its weight. The said hook pushes with its sloping lug 38 60 against a pin 39 carried by the lever 40 and therefore presses and moves the said lever 40 sidewise, which transmits the motion by means of a link 41 to the lever 42 and the lever 43, the said two levers being fixed 65 upon the same axis of rotation. The lever 43,

thereby moved upwardly, lifts by means of its pin 44 the bar 45 which effects the releasing of the buttons in the above described manner by the stirrups 46 being lifted. The stirrups which also effect the mutual releasing of the buttons of one and the same row and which, by depressing the buttons, have been dropped behind the cone or tooth 24 of the depressed button, release the last named button again. Therefore the stirrups 23 return back into their lowermost position and the entire lever system actuated by the same moves back again into its position of rest shown in Fig. 1, so that the receiver hook 3 returns in its initial position, the lug 36 80 moving so that it does not meet the pin 35.

If the receiver be taken off in case the selecting device had not been adjusted previously, for example, in case a subscriber had been called, the receiver hook will be pulled by the spring 8 only into the position indicated by dotted lines in Fig. 1, but its lug 36 does not meet at all the pin 35 during the said movement. The pin 39 likewise does not come in contact with the lug 38, the spring 8 having lifted the hook lever 3 just only up to the position indicated by dotted lines. This has for its object to prevent the button releasing device from going into action by merely taking off the receiver, for the reason that in this case the receiver hook has only to actuate the hook switch not shown in the drawing, which however takes place in ordinary manner. The device may also be utilized in such way that, the receiver being taken off, buttons can be adjusted, it is true, but the clock work is only allowed to be released after the receiver had been suspended and taken off, whereby the fault committed by the reversed manipulation will be compensated, without having any injurious influence upon the following action of the apparatus.

It is clearly seen that a lever or pointer like or otherwise arranged selecting device 110 may be connected mechanically in the same manner with the clock work, therefore the said modification also covered by the present invention needs not to be described and illustrated.

Claims.

1. In a device of the kind described, the combination of a clockwork mechanism including a spring, a selector device, means to lock said clock work releasably against 120 operation, mechanism connected to said means and operable by the operation of the selector device to release said clockwork, a receiver arm, and means controlled by the movement of the receiver arm to tension said 125 spring.

2. In a device of the kind described, the combination of a clockwork mechanism including a spring, a selector device, means to lock said clockwork releasably against 130

operation, mechanism connected to said means and operable by the operation of the selector device to release said clockwork, a receiver arm, means controlled by the movement of the receiver arm to tension said spring, and other means for restoring the selector device to original position after operation operable by movement of said receiver arm.

10 3. In a device of the kind described, the combination of a clockwork mechanism including a spring, a selector device, means to lock said clockwork releasably against operation, mechanism connected to said means and operable by the operation of the selector device to release said clockwork, a receiver arm, and other means carried by the receiver arm and engageable with the locking device to restore said device to locking position upon movement of the receiver arm in one direction.

20 4. In a device of the kind described, the combination of a clockwork mechanism in-

cluding a spring, a selector device, means to lock said clockwork releasably against operation, mechanism connected to said means and operable by the operation of the selector device to release said clockwork, a receiver arm, means controlled by the movement of the receiver arm to tension said spring, other means for restoring the selector device to original position after operation operable by movement of said receiver arm, and other means carried by the receiver arm and engageable with the locking device to restore said device to locking position upon movement of the receiver arm in one direction.

In testimony whereof I have hereunto set my hand in presence of two subscribing witnesses.

PHILIP RICHARDT.
